CLAIM

The ornamental design for a tamper evidence container closure, as shown and described.

DESCRIPTION

FIG. 1—Top, front, right side perspective view of a tamper evidence container closure;

FIG. 2—Front elevation view of the tamper evidence container closure of FIG. 1;

FIG. 3—Left side elevation view of the tamper evidence container closure of FIG. 1, the right side elevation view being a mirror image;

FIG. 4—Top plan view of the tamper evidence container closure of FIG. 1;

FIG. 5—Bottom plan view of the tamper evidence container closure of FIG. 1;

FIG. 6—Top, front, right side perspective view of another embodiment of a tamper evidence container closure;

FIG. 7—Front elevation view of the tamper evidence container closure of FIG. 6;

FIG. 8—Left side elevation view of the tamper evidence container closure of FIG. 6, the right side elevation view being a mirror image;

FIG. 9—Top plan view of the tamper evidence container closure of FIG. 6; and,

FIG. 10—Bottom plan view of the tamper evidence container closure of FIG. 6.

The dash-dash broken lines represent portions of the tamper evidence container closure that form no part of the claimed design.

1 Claim, 4 Drawing Sheets
